Attorney.

UNITED STATES PATENT OFFICE.

WILLIAM F. BAKER, OF BOSTON, MASSACHUSETTS.

ROD-FASTENER FOR STAIR-CARPETS.

1,258,853.

Specification of Letters Patent. Patented Mar. 12, 1918.

Application filed May 17, 1917. Serial No. 169,328.

To all whom it may concern:

Be it known that I, WILLIAM F. BAKER, a citizen of the United States, residing at Dorchester, Boston, in the county of Suffolk, 5 State of Massachusetts, have invented a certain new and useful Improvement in Rod-Fasteners for Stair-Carpets, of which the following is a specification, reference being had therein to the accompanying drawings.

10 My invention relates to securing means for engaging the rods which, in the laying of carpets on stairs, are frequently positioned in the corners between the risers and treads of said stairs for the purpose of holding said 15 carpet snugly within such corners.

One object of my invention is to provide a rod securer of the character above described having its parts so fashioned as to permit the location of said rod deeply within 20 the corner in which it is intended to lie. A further, and more especial object of my invention, is to provide a rod securer which, as well as the rod, is arranged to lie under 25 the carpet; the securer being adapted to lie below and just within the marginal edges of the said carpet and so as to be wholly concealed thereby, but having a construction which renders it easily operable in such concealed location, either to effect the engagement of said rod or the release of the 30 same.

Referring to the accompanying drawings forming a part of this specification, and in which like numerals of reference indicate 35 similar parts in the several views,

Figure 1 is a view in perspective showing a portion of a flight of stairs having a carpet rod secured thereon by means of a rod securer embodying my invention.

40 Fig. 2 is a front elevation and Fig. 3 an end view of my securer in its preferred form.

Fig. 4 is a side elevation of the same in a position permitting the engagement of the rod or the displacement of the same therefrom.

45 Fig. 5 is a side elevation of the same, showing the rod securer in a position adapted to secure said rod in place.

Fig. 6 is a view showing more especially 50 the manner of securing the stair-rod to the carpet.

Fig. 7 is a side elevation of the slide of the securer removed from the frame.

Having reference to the drawings,—

55 The rod securer comprises a frame 1 provided with the lugs 2 attached thereto;

which lugs afford means by which the frame may be attached preferably by screws in the desired location, upon the face of the riser of the stairs and adjacent the corner between 60 the riser and tread of the same. If desired, however, the securer may be attached to the tread of the stairs instead of to the riser.

The lower ends of the sides of the frame are prolonged into jaws 3, 3, which are concaved on the outer faces as shown, and provide seats adapted to receive the stair rod 4 designed to be secured in place thereby, the contour being preferably of a curvature closely conforming to the circumference of 70 the said rod. Said frame jaws 3, 3, are tapered to such thinness at the points, and the concavity of the same are so located with respect to the frame that a rod resting thereagainst will be positioned deeply within the 75 corner between the stair-riser and tread, the frame of course being so located upon the riser as to obtain the aforesaid location of the rod.

The frame is fitted with the slide 5 arranged to freely slide longitudinally therein but substantially rigid with respect to other movements relative to the frame; this result being preferably secured by a dovetailed engagement between the slide and 80 frame as more clearly shown in Fig. 3. The lower end of said slide 5 terminates in a forked portion which, at its deepest or upper part is interiorly concaved to closely fit astride the stair-rod, there being a front 85 jaw 5^a engaging the outer and upper quadrant of the circumference of the rod and the rear jaw 5^b engaging the inner and upper quadrant of said circumference. The curvature of the said rear jaw 5^b is arranged 90 to aline and register with that of the concaved lower ends of the frame jaws 3, 3. The points of said slide jaws 5^a and 5^b are slightly elongated as shown, but are always 95 sufficiently separated to provide for the free 100 passage of the rod between the same. The capacity for the longitudinal movement of the slide in respect to the frame should be such as to permit the slide 5 to be raised sufficiently to allow the rod 4 105 to pass under the point of the outer slide jaw 5^a as is shown in Fig. 4, and into the position wherein it becomes seated in place resting against the contoured portion of the frame-jaws 3, 3, the slide thereafter being forced downwardly until it is 110 astride the rod and rests firmly thereon.

If desired the provision of the rear jaw 5^b of the slide may be dispensed with, although I prefer to use the same.

The operative result of the foregoing construction is such that in the lowered position of the slide 5, the said rod 4, on its side adjacent the stair-riser, is engaged by the jaws 3, 3, of the frame; and it is also engaged on both sides by the jaws 5^a and 5^b of the slide. In this position the outside jaw 5^a of the slide operates not only to resist any force tending to pull the rod away from the stair-riser, but also prevents the displacement of the rod outwardly and away from the riser which must take place before there can be any upward movement of said rod past the shoulder formed by the top of the concaved seat of the jaws 3, 3, of the frame in response to any force pulling upwardly upon said rod. The fastener therefore in the lowered position of the slide is effective to secure said rod in its desired position.

While I prefer to construct my rod securer with coöperating sets of jaws which are contoured in close conformity with the circumference of the rod which is intended to be used in connection therewith, which jaws coöperate to secure the rod in the manner hereinbefore set forth, material departures from such contour may be permitted without especially impairing the efficiency of my device as a rod-securing means, so long as one of said sets of jaws provides a shoulder which limits the movement of the rod therewith when said rod is restrained from displacement from the plane of such movement sufficient to enable it to clear said shoulder, and the other coöperating set provides means operating to prevent the said displacement.

Ordinarily the arrangement hereinbefore described operates to secure the rod firmly in the desired position without additional locking means. However, to insure against any accidental displacement of the slide and release of the rod, a set-screw 6 may be provided in the slide which is adapted to engage the frame at the rear of said slide, in which case the said rear portion of the slide also

may be serrated or otherwise roughened as is shown at 8 in Fig. 4, or the frame may be drilled to permit a rod or pin 7 to be passed transversely therethrough so as to lie above said slide when it lies in its rod engaging position.

In employing a rod securer having the features of construction which I have hereinabove described, the frame of the securer is attached in position on the riser or tread before the carpet is laid, and the rods also, before such time, may be secured, preferably by tapes, 9 to the carpet at the desired location, leaving only a small portion of the rod end disengaged therefrom. When the carpet is laid, the slides of the rod-securer are lifted, the end of the rod secured to the carpet is slipped under the said slide into position against the frame jaws in which position it is secured by depressing the slide. All the necessary manipulations involved in these operations may be readily performed by the fingers operating between the edge of the carpet and the stairs; permitting the rod securer to be so located as to be entirely concealed from view. In similar manner, if desired to remove the carpet, this necessary operation can be also readily performed.

I claim as my invention:—

In a rod holder for carpet rods, a frame comprising a base having lateral raised portions which are provided, at one end of the same, with rod-seats so situated thereon as to position a rod lying therein in close proximity to the plane of the bottom surface of said frame, and a slide-jaw lying between the said raised portions and slidably mounted therebetween; said slide having a rod-seat at the end thereof arranged, in the rod-securing position of the slide, to coöperate with the rod-seats of said frame in fixedly securing said rod therewithin.

In testimony whereof I affix my signature in presence of two witnesses.

WILLIAM F. BAKER.
